UNITED STATES PATENT OFFICE.

GEORGE CSENGEY, OF SOUTH NORWALK, CONNECTICUT.

BOAT.

Application filed September 24, 1924. Serial No. 739,673.

To all whom it may concern:

Be it known that I, GEORGE CSENGEY, a citizen of the Republic of Hungary, residing at South Norwalk, in the county of 5 Fairfield and State of Connecticut, have invented new and useful Improvements in Boats, of which the following is a specification.

My present invention pertains to boats of 10 the kind that are designed to be propelled and steered by one or more persons, and one of its objects is the provision of manually operable propelling means that is simple, inexpensive, strong and efficient.

15 Another object of the invention is the provision of steering means adapted to be readily controlled by a single person without interfering in any degree with the effort of such person in propelling the boat.

20 To the attainment of the foregoing, the invention consists in the improvement as hereinafter described and definitely claimed.

In the accompanying drawings, forming part of this specification:—

25 Figure 1 is a side elevation showing a boat equipped with the preferred embodiment of my invention.

Figure 2 is a top plan view of the same.

30 Figure 3 is a detail longitudinal vertical section taken in the plane indicated by the line 3—3 of Figure 2.

Figure 4 is a detail perspective of the pedal lever employed in the steering of the boat.

35 Figure 5 is a rear end elevation of the boat.

Similar numerals of reference designate corresponding parts in all of the views of the drawings.

40 The hull 1 of the boat may be and preferably is of the ordinary well known type such as generally employed in row boats.

45 Journalized in suitable bearings 2 at the stern of the boat is a substantially upright shaft 3, equipped on its lower portion with a rudder 4 and on its upper end with a T-head 5.

Pivots connected at 6 to the T-head 5 are open links 7 with which are interlocked forwardly extending rods 8. These rods 8 extend under and forwardly beyond the rear intermediate seat 9 of the boat and are interlocked at their forward ends with the apertured end portions of a pedal lever 10. 55 The said pedal lever 10 is disposed on the bottom of the hull and slightly in advance

of the seat 9 and in addition to the apertured end portions alluded to the lever 10 is provided with rearwardly deflected end portions 11, the said end portions 11 being designed to prevent the feet of an operator from slipping off the lever. As best shown in Figure 4 the lever 10 is riveted at 12 or is otherwise fixed to a body 13 formed like the lever of appropriate metal and provided 60 with lower and upper apertured flanges 14. These latter receive an upright shaft 15 on the bottom of the hull so as to enable the body 13 and the lever 10 to freely swing about the shaft, and the body is secured on 70 said shaft 15 by a cotter pin 16 and washer 17 or other appropriate means in the discretion of the manufacturer.

Manifestly when disposed on the seat 9 an operator is enabled with his feet to conveniently steer the boat and this without requiring any action whatever with his or her hands.

Fixedly secured on the gunwales of the hull 1 are holders 20 and fixedly secured on 80 the bottom of the hull and spaced inwardly from said gunwales are standards 21 on the upper ends of which are holders 22 in coincidence with the holders 20. The said holders are arranged in transverse alignment and each pair of holders 20 and 22 receives a sleeve 23 which is held against turning in the holders by the clamping action of the holders or otherwise in the discretion of the manufacturer.

Journalized in the sleeves 23 are transverse shafts 24, and fixed to the shafts 24 outwardly beyond the sleeves 23 are rods 26 which are equipped with propelling blades at 27. In the attachment of the said rods 26 according to the preferred embodiment of my invention, the said rods are passed diametrically through the shafts 24 and also through collars 28 on the end portions of the shafts, and are fixed to the shaft by said screws 29 which bear in the ends of the shafts 24 as 90 illustrated.

The inner ends of the shafts 24 are spaced apart a considerable distance as appears in 105 Figure 2, and to said inner end portions of the shafts 24 are connected the arms of a U-shaped handle 30. In the preferred embodiment of the invention the said handle arms are extended diametrically through the shafts 24 and also through collars 31 on the 110 shafts and both handle and collars are adjustably fixed to the shafts by set screws 32.

The adjustable connection of the handle 30 to the shafts 24 is particularly advantageous inasmuch as it permits of the transverse portion of the handle 30 being conveniently arranged relative to the seat 9 and also to a seat 9^a arranged at the opposite side of the vertical plane of the shafts 24 with reference to the seat 9.

A roller 33, preferably of wood, fiber or the like, is mounted on the transverse portion of the handle 30 so as to freely turn about the said transverse portion. The said roller 33 which constitutes a hand grasp is of considerable length so that the occupants 15 of both of the seats 9 and 9^a may participate in the rotation of the shafts 24 and the propellers through the medium of the hand grasp or roller 33 and the handle 30. It will also be readily apparent that the boat 20 may be propelled and steered by a single person irrespective of whether such person is on the seat 9 and is facing forward or is on the seat 9^a and is facing rearward. I would have it understood, however, that the 25 general arrangement disclosed is provided in order that two persons seated on the two seats 9 and 9^a may participate in the propulsion of the boat while the person on the seat 9 and facing forward has for his or 30 her province to steer the boat through the medium of the pedal lever 10.

It will be appreciated from the foregoing that my improvement while highly efficient for the purposes indicated does not detract 35 in any measure from the finished appearance of a boat, but on the other hand is calculated to enhance such finished appearance.

I have specifically described the preferred embodiment of my invention in order to impart 40 an exact understanding of said embodiment. I do not desire, however, to be understood as confining myself to the construction and relative arrangement of the parts as disclosed inasmuch as the scope of 45 my invention is defined by my appended claims within which changes or modifications may be made without departure from my invention.

Having described my invention, what I 50 claim and desire to secure by Letters Patent, is:—

1. The combination of a boat hull, a shaft journaled in bearings on the stern of the hull and having a rudder and also having a T-head, a horizontally swinging pedal lever mounted on the bottom of the hull; and rods connected with the T-head of the rudder and the end portions of the said 55 pedal lever; the said T-head having apertured end portions, and the said rods being connected with the T-head by open links interlocked with the rods and having portions journaled in the ends of the T-head.

2. The combination of a boat hull, a shaft journaled in bearings of the stern of the hull and having a rudder and also having a T-head, a horizontally swinging pedal lever mounted on the bottom of the hull; and rods connected with the T-head of the rudder and the end portions of the said 60 pedal lever, the said pedal lever having rearwardly deflected end portions, and being fixed to the intermediate portion of a body having upper and lower apertured flanges, and the said flanges of the body being mounted on and adapted to swing about a shaft fixed to and rising from the bottom of the hull.

3. The combination of a boat hull having gunwales, holders fixed on said gunwales, standards fixed on the hull bottom and spaced inwardly from the gunwales, holders on said standards and arranged in coincidence with the first-named holders, the said standards being spaced a considerable distance apart, sleeves secured in the said holders and spaced apart, shafts journaled in said sleeves and spaced apart, propellers having rods extending diametrically through the outer portions of said shafts and also having blades on the rods, set screws bearing in the outer ends of the shaft and against said rods, a U-shaped handle having a transverse portion and also having end portions extending diametrically through the inner end portions of the shafts, set screws bearing in said shafts and adjustably fixing the handle thereto, and a roller mounted on the transverse portion of the handle.

In testimony whereof I affix my signature.
GEORGE CSENGERY.
